(57) **CLAIM**

The ornamental design for an alarm clock with calendar and thermometer, as shown and described.

DESCRIPTION

The claimed alarm clock with calendar and thermometer is a clock that can be set to sound a bell or buzzer at a desired hour with the function of reckoning time and measuring temperature.

FIG. 1 is a front elevational view of an alarm clock with calendar and thermometer showing my new design;

FIG. 2 is a rear elevational view thereof;

FIG. 3 is a right side view thereof;

FIG. 4 is a left side view thereof;

FIG. 5 is a top plan view thereof;

FIG. 6 is a bottom plan view thereof;

FIG. 7 is a perspective view thereof; and,

FIG. 8 is a right side view thereof with the stand being pulled out.
